UNITED STATES PATENT OFFICE.

JOHN M. FULTON, OF ROANOKE, INDIANA, ASSIGNOR OF TWO-THIRDS TO
JAMES H. McCAHON AND ERVIN E. RICHARDS, OF SAME PLACE.

THILL-COUPING.

SPECIFICATION forming part of Letters Patent No. 291,588, dated January 8, 1884.

Application filed May 24, 1883. (No model.)

To all whom it may concern:

Be it known that I, JOHN M. FULTON, a citizen of the United States, residing at Roanoke, in the county of Huntington and State of Indiana, have invented a new and useful Thill-Coupling, of which the following is a specification, reference being had to the accompanying drawings.

This invention relates to shaft-couplings for vehicles; and it has for its object to provide for the adjustment of the coupling-box laterally in relation to the shackle, whereby thills may be substituted for a single pole, and vice versa, without moving the shackles upon the front axle, as has heretofore usually been necessary, owing to the difference in width usually existing between these parts.

My invention consists in the improved construction and arrangement of parts which will be hereinafter fully described, and particularly pointed out in the claims.

In the drawings hereto annexed, Figure 1 is a perspective view. Fig. 2 is a longitudinal vertical sectional view. Fig. 3 is a vertical transverse sectional view; and Fig. 4 is a detailed view, showing in perspective the several parts forming my invention detached from each other, so as to illustrate more clearly the construction of each.

30 The same letters refer to the same parts in all the figures.

A in the drawings designates a clip or shackle, upon the front side of which is formed a projection or box, B, having a recess, C, and provided at its rear or inner end with a transverse groove, D, which may be of any suitable shape. It is also provided in front of the groove D with a transverse slot, E, to receive a sliding bolt, as will be presently described.

F is the coupling-box, which consists of a body, G, having forwardly-projecting ears or lugs H H, between which the eye of the thill-iron is pivoted upon a bolt, I. The body G is provided with a rearwardly-projecting shank, J, extending into the recess C, in which it is capable of adjustment laterally. The shank J is provided at its rear end or edge with a flange, K, fitting in the groove D in box B. 50 Shank J is also provided with a vertical perforation, L, for the coupling-bolt M. The

bolt I, by which the thill-iron N is pivoted between the ears or lugs H H, is provided with a feather, O, for the accommodation of which the eye of the thill-iron is provided with a suitable groove or recess. One of the ears H is also provided with an opening for the insertion of the said feather, which when the bolt is inserted to its proper position and the thill-iron lowered, prevents the withdrawal of the bolt, and thus locks the thill or shaft in position. The recess O of the box B is fitted with a cap, P, having at its front edge a flange, Q, which rests against the coupling-box F and serves to brace the latter against the strain to which it will be exposed. The cap P has a recess, R, and a transverse slot, S. In the said recess is fitted a nut, T, which may have a transversely-sliding movement. A plate, U, secured to the under side of cap P, serves to hold the nut 70 T in its place.

The coupling-bolt M, to which reference has been made above, is passed from the top of the box B through the slot E, through the perforation L in the shank J of the coupling-box, and through the slot S in the cap P, where it engages the nut T. The latter, it will be seen, is prevented from turning by the recess in which it is seated, thus enabling the bolt to be tightened into place. When the 80 bolt is slightly loosened, the shank J of the coupling-box may be adjusted laterally in the recess C, the slots E and S permitting lateral adjustment of the coupling-bolt, and the recess R being of sufficient dimensions to admit 85 of the adjustment of the nut T, as stated. In this manner the coupling-box may be moved laterally to the desired extent without changing the position of the shackle upon the axle. The flange K upon the shank J, which is fitted, 90 as set forth, in the groove D of box B, takes up the strain to which the coupling-bolt M would otherwise be subjected, thus preventing the said bolt from bending or giving way when draft is applied to the thills or shaft.

Upon the bolt M, directly under its head, is fitted a small plate or washer, W, which serves to prevent dust and dirt from entering through the slot E.

From the foregoing description, taken in connection with the drawings hereto annexed, the operation and advantages of my invention

will be readily understood. It is simple, inexpensive, and useful for the purposes set forth.

Having thus described my invention, I claim 5 and desire to secure by Letters Patent of the United States—

1. The combination, with a clip or shackle having a forwardly-projecting recessed box, of a coupling-box having a rearwardly-extending shank, secured laterally adjustably in the said recessed box, substantially as set forth.

2. The combination of the clip or shackle having a forwardly-extending box having a transverse groove in its inner rear end, with 15 the coupling-box having a rearwardly-extending shank secured laterally adjustably in the said box, and having at its rear end an upwardly-extending flange fitting in the groove in the recessed box of the clip, substantially as set 20 forth.

3. The combination of a clip or shackle having a forwardly-extending recessed box with 25 a transversely-slotted bottom, a transversely-slotted cap for the said box, a coupling-box having a rearwardly-extending vertically-perforated shank capable of being adjusted transversely in the said recessed box, and a coupling-bolt and nut, substantially as set forth.

4. The combination of a clip or shackle having a forwardly-extending recessed box with a transversely-slotted bottom, a transversely-slotted cap for the said box, provided with a recess in its under side, a nut seated in the said recess, a covering-plate, a coupling-box 30 having a rearwardly-extending vertically-perforated shank capable of being adjusted transversely in the said recessed box, and a coupling-bolt, all arranged and operating substantially as set forth.

5. The combination of the transversely-slotted box extending forward from the clip or shackle, the transversely-slotted cap for the said box, the coupling-box having a rearwardly-extending vertically-perforated shank, the 45 coupling-bolt and nut, the latter seated in a transverse recess in the cap-plate, and a protecting plate or washer arranged upon the upper end of the bolt, adjoining the head of the same, as and for the purpose set forth.

In testimony that I claim the foregoing as my own I have hereto affixed my signature in presence of two witnesses.

JOHN M. FULTON.
